ELECTRODE HOLDER

Albert H. Smith, South Gate, Calif.

Application March 29, 1937, Serial No. 133,488

11 Claims. (Cl. 219—8)

My invention relates to an electrode holder. An object of the invention is to provide cam means for operating gripping jaw means comprised in the invention.

5 Another object is to provide in a comparatively small handle compact operative mechanism for the jaw means.

Still another object is to provide a convenient operating lever for said mechanism, which can 10 be operated by the same hand that carries the handle.

A further object resides in providing gripping jaws that may be easily removed for repair or replacement.

15 The invention also comprises novel details of construction and novel combinations and arrangements of parts, which will more fully appear in the course of the following description.

In the drawing, like reference characters designate similar parts in the several views.

Figure 1 is a side elevation of an embodiment of my invention.

Figure 2 is a longitudinal section through said embodiment.

25 Figures 3 and 4 are respectively sections taken on the lines 3—3 and 4—4 of Figure 2.

Referring more in detail to the drawing, the reference number 5 designates a conductive cable for conducting electrical current to the device.

30 Insulation 6 is provided around the cable. A fluted, insulating grip is shown at 7. Concentric within the grip 7 is an insulating sleeve 8, and concentric within the sleeve is a metal tube 9. The cable 5 is fastened to the rear end of the tube

35 9 by means of a clamping plate 10 curved to receive the round surface of the cable. A nut and bolt 12 and 13 maintain the clamping plate in position.

Extending from side to side in the tube 9, ahead 40 of the clamping plate, is a pin 14. Grooved to receive the pin 14 is a circular washer 15 of insulating material. Opposed thereto is another washer 16, also of insulating material. A coil spring 17 is disposed between the washers 15 and

45 16. Surrounding the spring 17 and also arranged between the washers and within the tube 9 is an insulating bushing 18. The bushing 18 is approximately the length of the coil spring 17 when same is fully compressed.

50 The tube 9 is split at 19 to receive a sliding abutment 20, preferably of the same material as, and integral with the washer 16. Arms 21 connect the sliding abutment 20 with a sliding cam 22. Pins 23 and 24 fasten the arms to the abutment and to the cam. The arms are re-

cessed, as indicated at 25, to permit longitudinal movement of the arms relative to a transverse pivot pin 26, upon which is pivotally mounted a lever 27.

The lever 27 has an insulating casing 28, which provides a handle. The lever projects through the opening 19 in the tube 9 and through an opening 29 in the sleeve 8. The grip 7 likewise has an opening 30 in which the lever 27 may reciprocate. The openings 19, 29 and 30 are of course aligned in superposed relation by reason of such relation of their concomitant parts.

A link in the form of a swinging hook or yoke 31 is mounted on the cam 22, and the front end of the cam is a curved, inclined cam face 32. 15 Pivoted on a spindle 33 is a normally upper jaw 34. A shank 35 of the upper jaw has a curved face 36 to engage the curved face of the cam. The normally upper edge of the shank 35 is notched at 37 to receive the hook or yoke 31. 20

The upper jaw proper 38 is faced with a protective, conductive covering 39. The covering 39 protects three sides of the jaw 38 and an insulating head 40 protects the fourth or normally the top side. Cooperating dents and recesses 41 25 and 42 in the covering 39 and the jaw 38 respectively maintain the covering in place. When thin or worn by use, the covering may be replaced. A boss 43 and a screw 44 respectively hold the insulating head 40 on the jaw 38 and prevent the head from turning thereon. The boss fits in a corresponding recess in the jaw 38.

The forward end 45 of the tube 9 is semi-cylindrical, the normally upper half being removed. Within this semi-cylindrical portion 45 of the 35 tube is a lower jaw 46 provided with electrode receiving notches 47. A head member 48 of the lower jaw is held within the forward end of the tube 9 by the pin 33. The outwardly protruding lower jaw 46 is removably held within the semi-cylindrical portion 45 by means of screws 49 and 149 screwed into a flange 53 and into the head 48 of the lower jaw, respectively.

Insulation for the front end of the tube 9 and the lower jaw consists of an insulating ring 50 45 having an integral protruding semi-cylindrical covering 51 nesting the lower jaw. A screw 52 maintains the insulation 50 and 51 in place and also passes through both the portion 45 and the flange 53 on the lower jaw. A screw 60 fastens 50 the grip 7 on the sleeve of the holder.

In the use of the device, an electrode 54 is clasped by the jaws 34 and 46 and held in one of the notches 47 in the lower jaw. The operation is as follows:

The conductive tube 9 is connected in an electric circuit (not shown) by means of the cable 5. To open the jaws, the handle 28 is pressed toward the body of the holder, in the direction 5 of arrow "A" of Figure 1. This movement of the handle causes its associated lever 27 to move the abutment 20 and washer 16 rearward (to the left in Figure 2). This movement of the abutment and washer compresses the spring 17, 10 and draws the cam rearwardly too, through the intermediary of the arms 21. Rearward movement of the hook or yoke 31 on the cam draws the hook or yoke from the notch 37, forcing the shank 35 downward, considering the tool in the 15 position shown in Figure 2. The upper jaw 34 is thereby swung upwardly, releasing the electrode.

The upper jaw is closed by releasing the handle 28, which permits the tension placed in the 20 spring 17 to move the washer 16, abutment 20, arms 21 and cam 22 forward. Forward movement of the cam toward the jaws causes the shank face 36 to ride upward on the cam face 32 and causes the hook or yoke to again seat 25 itself in the notch 37. Upward movement of the shank 35 of course causes downward closing movement of the upper jaw (as they are shown in Figure 2). It is to be understood that the hook or yoke 31 seats itself in the notch 37 when the tool is turned with the lever 28 pointing 30 upward (e. g., such as shown in Figures 1 and 2). When the tool is tipped to a position in which the lever 28 points downward and the lever is released, the jaw 38 drops (being pointed 35 downward), thus raising the shank 35 and allowing the hook to fall from its engaged notch 37.

It will be noted that an electrode is held between the jaws without operation of the handle 28 by the user, and that the electrode may 40 be released by the user employing fingers of the same hand that holds the tool. In each of these operations, therefore, the user's other hand is free.

When the covering 39 of the upper jaw becomes 45 worn, it may be replaced in the manner described, and when it is desired to replace the lower jaw, removing the screw 52 will permit the removal of the insulation 50, 51 and removing pin 33 and screws 49 will permit removal of the entire lower jaw.

It will be noted in Figures 3 and 4 the manner in which the surrounding insulation holds the pin 26 and the spindle 33 in place. I prefer to 50 use an insulating material for the abutment 20, to prevent its binding in the slot 19 of the tube 9 by reason of a metal-to-metal contact.

While I have illustrated and described what I now regard as the preferred embodiment of my 55 invention, the construction is, of course, subject to modifications without departing from the spirit of my invention. I, therefore, do not wish to restrict myself to the particular form of construction illustrated and described, but desire to 60 avail myself of all modifications which may fall within the scope of the appended claims.

Having thus described my invention, what I claim and desire to secure by Letters Patent is:

1. In an electrode holder, an electrode holding 70 jaw pivoted on the holder, an element movable longitudinally of the holder and arranged to effect pivotal movement of the jaw by its said longitudinal movement, spring means connected to effect movement of said element longitudinal of 75 the holder, and means on the holder arranged

to move the element longitudinally thereof against the action of the spring.

2. In an electrode holder, an electrode holding jaw pivoted on the holder, compressible spring mechanism to automatically lock the jaw in a closed position, said mechanism being manually movable to a position in which the jaw is unlocked, and manual means to compress the spring to render it inoperative and to move the mechanism to a position in which the jaw is unlocked. 10

3. In an electrode holder, an electrode holding jaw pivoted on the holder, a cam movable longitudinally of the holder into driving engagement with the pivoted jaw, and arranged to 15 cause closing movement of the jaw by said driving engagement, and lever means connected to withdraw the cam in a direction away from driving engagement with the pivoted jaw, to unlock the pivoted jaw. 20

4. In an electrode holder, an electrode holding jaw pivoted on the holder, a cam movable longitudinally of the holder, means connected with the pivoted jaw to engage the face of the cam and cause closing movement of the jaw by longitudinal movement of the cam in one direction, lever means connected to withdraw the cam from 25 its jaw closing position, and an element connected with the cam to move the jaw to an open position. 30

5. In an electrode holder, an electrode holding jaw pivoted on the holder, a cam movable longitudinally of the holder, means connected with the pivoted jaw to engage the face of the cam and cause closing movement of the jaw by longitudinal movement of the cam in one direction, lever means connected to withdraw the cam from 35 its jaw closing position, and a link pivoted on the cam and engaging said means, to open the jaw by the withdrawing movement of the cam. 40

6. In an electrode holder, an electrode holding jaw movable on the holder, the jaw having a notched shank, a lever fulcrumed on the holder, means to close the jaw when the lever is released, and a link seated in the notch of the shank when the jaw is closed and connected to open the jaw when the lever is operated to actuate said means in a given direction. 45

7. In an electrode holder, an electrode holding jaw pivoted on the holder, a cam arranged to move the jaw to a closed position, a lever to withdraw the cam, means connected with the cam to open the jaw upon such cam-withdrawing movement, and spring means arranged to urge the cam to a jaw-locking position and to resist jaw-opening movement of said means. 50

8. In an electrode holder, an electrode holding jaw movable on the holder, a lever fulcrumed on the holder, an abutment on one side of the lever arranged to be moved by the lever in one direction, spring means arranged to resist said movement and to move the abutment in the opposite direction, a cam on the opposite side of the lever from the abutment, means connecting the cam and the abutment past the lever, the cam 65 being arranged to move the jaw to a closed position and means connecting the cam and jaw to move it to an open position by a different movement of the cam.

9. In an electrode holder, a conductive tube, 70 an electrode holding jaw removably mounted in the tube against relative movement, a jaw pivoted on the first-mentioned jaw, means to move the pivoted jaw to a closing position, and means to move said jaw to an open position, the jaws, 75

upon removal of their pivoted connection, being removable together from the conductive tube, the means to move the pivoted jaw to open and closed positions having a connection with said unit that is capable of being disconnected.

5. 10. In an electrode holder, a conductive tube, an electrode holding jaw removably mounted in the tube against relative movement, a jaw pivoted on the first-mentioned jaw, means to move the pivoted jaw to a closing position, and engaged hook-and-notch means to move said jaw to an open position, the jaws, upon removal of their pivoted connection, being removable together from the conductive tube, the hook being arranged to fall from its engage notch by tip-

ping of the holder, to disconnect the unit from said jaw-opening means.

11. In an electrode holder, an electrode holding jaw pivoted on the holder, means arranged to be moved longitudinally of the holder, said means being connected to move said jaw pivotally, when actuated, spring means disposed when compressed to move said means longitudinally of the holder in one direction, and lever means arranged to move the first-mentioned 10 means longitudinally of the holder in the opposite direction, the last mentioned movement compressing the spring means.

ALBERT H. SMITH.
